UNITED STATES PATENT OFFICE.

JOSEPH DUCHESNEAU, OF LEOMINSTER, MASSACHUSETTS, ASSIGNOR, BY MESNE ASSIGNMENTS, TO THE DE-LITE-US SPRING CLASP CORPORATION, OF NEW YORK, N. Y., A CORPORATION OF NEW YORK.

FLYING TOP.

Application filed February 3, 1927. Serial No. 165,524.

The object of my invention is to provide a top of this class which can be mounted on a stick and spun by a string being pulled so that the top will leave the stick and fly into the air. This object is accomplished by my invention, one embodiment of which is hereinafter more particularly set forth.

For a more detailed description of my invention, reference is to be had to the accompanying drawings, forming a part hereof, in which

Figure 1 is a perspective view of my improved top mounted on a stick and about to be actuated so that it will leave the stick and fly.

Figure 2 is a view, partially in section, showing the mounting on the top on the stick.

Throughout the various views of the drawings similar reference characters designate similar parts.

My improved top 1 may be mounted on a handle 2 and actuated by a string 3 which is pulled in the manner in which strings are generally pulled to actuate tops.

The top 1 is provided with a celluloid or similar cylinder 4 adapted to turn freely on the reduced end 5 of the handle 2 and this cylinder has a collar 6 mounted a little above its lower end which forms a flange to limit the string in one direction and at its upper end it has a similar collar 7 so that the string 3 may rest on the cylinder 4 between the flanges 6 and 7. The top 8 of the cylinder 4 is perforated to receive an eyelet 9 which secures the top to the blades 10 and 11, these blades being preferably formed of celluloid and formed, as shown, that is the blades 10 are made of one piece and the blades 11 of another and all the parts which are made of celluloid, that is, 7, 8, 10 and 11, are preferably held together by a suitable cement or by the welding power of celluloid itself when

heated and softened so that a very light and strong structure is made, as above set forth. 45

In view of the foregoing, the operation of my device will be readily understood. Assuming that the flying top 1 is placed on the stick 2 in the manner indicated after the string 3 is properly wound on the cylinder 4, as above stated, the handle and string are then held, as indicated in Figure 1, and a sudden strong pull is given to the string 3 and thereby the top 1 is made to rotate at a high speed. This rotation causes 55 the top to rise off the handle 2 and fly into the air and it continues to fly as long as its rotation is sufficient to maintain it.

While I have shown and described one embodiment of my invention it is obvious 60 that it is not restricted thereto, but that it is broad enough to cover all structures that come within the scope of the annexed claims.

Having thus described my invention, what I claim is:

1. In a device of the class described, a stick having a cylindrical end adapted to receive a cylinder, propeller blades rigidly secured to a cylinder by an eyelet so that when a string is withdrawn from the string receiving portion, with a sudden pull, the cylinder, and the parts rigidly connected thereto, will fly into the air. 65

2. A flying top comprising a celluloid cylinder with a top, projecting flanges secured to the cylinder to define a string receiving portion, propeller blades, an eyelet connecting the propeller blades with the top of the cylindrical portion, whereby the cylindrical portion and its attached parts form practically an integral unit which may be driven into the air by the pull of a string. 75

In testimony whereof, I have hereunto set my hand this 25th day of January, 1927.

JOSEPH DUCHESNEAU.
